(57) **CLAIM**

The ornamental design for a “head protecting device for a golf cart roof,” as shown and described.

DESCRIPTION

FIG. 1 is a front, left perspective view of a head protecting device for a golf cart roof showing our new design, wherein the front, right perspective view is a mirror image thereof; FIG. 2 is a bottom, left perspective view thereof, wherein the bottom, right perspective view is a mirror image thereof; FIG. 3 is a back, left perspective view thereof, wherein the back, right perspective view is a mirror image thereof; FIG. 4 is an angled, front, left perspective view thereof, wherein the front, right perspective view is a mirror image thereof;

FIG. 5 is a front elevation view thereof;

FIG. 6 is bottom view thereof;

FIG. 7 is a back elevational view thereof;

FIG. 8 is a top view thereof; and,

FIG. 9 is a top, left perspective view thereof, wherein the top, right perspective view is a mirror image thereof.

1 Claim, 4 Drawing Sheets
